CLAIM

The ornamental design for a massage element, as shown and described.

DESCRIPTION

FIG. 1 is a perspective view of the present invention;

FIG. 2 is a front elevational view of the present invention shown in FIG. 1, the right side, left side and rear elevational views being mirror images thereof;

FIG. 3 is a top plan view of the present invention shown in FIG. 1;

FIG. 4 is a bottom plan view of the present invention shown in FIG. 1;

FIG. 5 is a perspective view of the present invention;

FIG. 6 is a front elevational view of the present invention shown in FIG. 5, the right side, left side and rear elevational views being mirror images thereof;

FIG. 7 is a top plan view of the present invention shown in FIG. 5;

FIG. 8 is a bottom plan view of the present invention shown in FIG. 5; and,

FIG. 9 is a front elevational view of the present invention shown in FIG. 6 with a portion shown in cross-section.

The broken lines in the figures are for the purpose of illustrating portions of the massage element that form no part of the claimed design.

1 Claim, 9 Drawing Sheets
